UNITED STATES PATENT OFFICE.

HARRY M. CLOUDE, OF CINCINNATI, OHIO.

PUMP-PLUNGER.

1,248,263.

Specification of Letters Patent. Patented Nov. 27, 1917.

Application filed March 16, 1917. Serial No. 155,273.

To all whom it may concern:

Be it known that I, HARRY M. CLOUDE, a citizen of the United States, and a resident of Cincinnati, in the county of Hamilton and State of Ohio, have made certain new and useful Improvements in Pump-Plungers, of which the following is a specification.

My invention relates to improvements in pump plungers or pistons, and it consists in the combinations, constructions and arrangements herein described and claimed.

An object of my invention is to provide a plunger for use with pumps either of the pneumatic or the hydraulic type which will hug the interior of the cylinder closely when making a compression stroke, but which will retract readily from the walls of the cylinder when moving in the opposite direction.

A further object of my invention is to provide a plunger having a resilient cup packing with means for keeping the ends of the cup packing from leaving the walls of the cylinder while permitting the body portion to retract from the walls so as to decrease the friction during the stroke of the plunger in one direction and to force the body portion of the cup packing into close contact with the walls during the stroke in the opposite direction.

A further object of my invention is to provide a plunger or piston in which the parts may be readily assembled or replaced.

Other objects and advantages will appear in the following specification, and the novel features of the invention will be particularly pointed out in the appended claims.

My invention is illustrated in the accompanying drawings which form a part of this application, in which:—

Figure 1 is a side view of a double acting pump having a plunger constructed according to my invention.

Fig. 2 is an enlarged section through the plunger shown in Fig. 1.

Fig. 3 is a section through a modified form of the device.

Fig. 4 is an end of the plunger shown in Fig. 3, and

Fig. 5 is a perspective view of one of the cup packings.

Referring now to Fig. 3 I have shown therein a plunger rod 1 having a reduced portion 2 which is threaded at the end as shown at 3. Carried by the reduced por-

tion is a plate 4 which abuts the shoulder 5 formed at the junction of the reduced portion with the main body portion. The plate 4 is provided with a hub 4^x which abuts a similar hub 6^x of a plate 6, these hubs 4^x and 6^x extending through a central opening of a resilient washer 7. The hub 6^x of the plate 6 on the opposite side of the plate extends through the opening 8^x of the cup packing 8. The form of the latter is shown in Fig. 5. It consists of a buckskin or other suitable member having a cylindrical shape with a closed end which is provided with the opening 8^x, mentioned above.

On the inside of the buckskin cup packing is a leather washer 9 which is held by means of a plate 10 whose hub 10^x abuts the hub 11^x of a plate or disk 11. The latter is provided with a series of openings 11^y, and is held in position by means of a nut 12.

From the foregoing description of the various parts of the device, the operation thereof may be readily understood. Assume that the plunger is moving in the direction shown by the arrow in Fig. 3 in a cylinder 13 whose walls are indicated by dotted lines. The fluid which is being pressed upon by the plunger enters the openings 11^y and forces the resilient cup packing 8 tightly against the walls of the cylinder. In the reverse stroke the cup collapses so that the friction on the walls of the cylinder is reduced.

It will be observed that the free end of the cup is substantially flush with the outer portion of the plate 11. Without this plate 11 to keep the free ends of the cup in position these ends will be forced inwardly toward the axis of the plunger under the compression stroke, instead of being forced outwardly as they are when air enters the space or chamber 14 between the plate 11 and the plate 10.

In Fig. 1 I have shown the construction in which a plunger or piston is provided with means for preventing the leakage of the fluid past the plunger, no matter in what direction the plunger is moving. The plunger is shown in connection with a pump of the double acting type, that is to say one in which the main cylinder 15 is connected at its ends to a common pipe 16 communicating with a tube 17 leading to the source of exit for the compressed air, suitable check valves 18 and inlet valves 19 being provided.

In Fig. 2 the parts 8', 9', 10' and 11' cor-

respond to the parts 8 to 11 in Fig. 3. It will be observed that the plate 11' is first placed in position. Afterward the parts are arranged in their order from left to right.

- 5 The nut 12 holds all the parts together upon the reduced portion 2 of the plunger rod 1.

In this instance when the plunger moves toward the left in Figs. 1 and 2 compressing the air before it, the air will enter the chamber 14' in Fig. 2 and press the cup 8' into close contact with the walls and cylinder 13'. The cup 8 will be deflated, that is to say, it will retract from the walls thereby presenting less friction. In Fig. 2 I have shown 15 the manner in which the cup retracts. The extent of this retraction is exaggerated purposely for the sake of illustration. The provision of the plates 11 and 11' insures the proper working of the device since it 20 absolutely prevents the air from entering between the free ends of the cup and the walls of the cylinder. Since the cups are held tight to the walls in the compression strokes, the efficiency of the plunger is very 25 high.

I claim:

1. A plunger comprising a plunger rod, a plate or disk carried by said rod, a cup packing carried by said plate or disk, said cup being disposed between the plate or disk and the inner walls of the cylinder, a plate rigidly secured to said plunger and spaced apart from said first named plate, the ends 30

of the second named plate being in engagement with the interior portion of the cup, 35 said last named plate being perforated.

2. A plunger or piston comprising a plunger rod, a plate or disk carried by the rod, a flexible cup packing having a closed end in engagement with said plate, an auxiliary 40 plate for holding the closed end of the cup in engagement with the first named plate, said second named plate being disposed within the cup, and a third plate also disposed within the cup and spaced from said 45 second named plate, said third named plate being in constant engagement with the interior walls of the cup and being perforated.

3. A plunger or piston comprising a plunger rod, a plate or disk carried by the rod, a 50 flexible cylindrical cup packing having a closed end in engagement with said plate, a second plate for holding the closed end of the cup in engagement with the first named plate, said second named plate being disposed within the cup, and a third plate also disposed within the cup and spaced from said 55 second named plate, said third named plate being in engagement with the interior walls of the cup and being perforated, said 60 second named plate and said third named plate having abutting hubs and a nut carried by said plunger rod and arranged to bear on said third named plate for holding the parts together.

HARRY M. CLOUDE.
